METHOD AND APPARATUS FOR MAKING
JOINTS IN WOVEN WIRE FABRICEdward J. Buell, Niagara Falls, N. Y., and Francis
D. Martin, Niagara Falls, Ontario, CanadaApplication January 18, 1936, Serial No. 59,750

12 Claims. (CL. 140—3)

The present invention pertains to a method, and apparatus for making joints in woven wire fabric and is well adapted for the manufacture of seams in Fourdrinier wires. Heretofore, efforts have been made to connect the ends of the belt by aligning the warp pickets on each side of the seam, and connecting them through the medium of an interposed strip either of fusible, or non-fusible material by the application of heat. Where the interposed strip has a non-fusible core and a fusible coating, it is not so important that the warp pickets be aligned, but in each case, it is necessary to hold the ends of the fabric in contact with the interposed strip during the heating operation.

The relatively fine mesh and large width of Fourdrinier wires have heretofore, been regarded as insurmountable difficulties in the development of a machine that is moved at uniform rate across the width of the fabric. These difficulties have been augmented in those seams where heat is employed, for in such instances, heat conducting blocks must be used to protect the work from being overheated, and these normally require resetting at short intervals. The resetting of the blocks usually requires resetting of the fabric to insure uniformity of the finished product, all of which not only requires considerable time, but increases the opportunity for failure in the attainment of a correctly made joint.

An object of our invention is the provision of a method and apparatus by means of which wire joints can be made continuously in a woven wire fabric, notwithstanding the relatively fine mesh of which the fabric is made, and the width of the belt on which the seam is intended to be used. The invention is applicable not only for making seams in which a strip containing fusible material is interposed between the ends of the fabric, but also in making other types of seam, which do not necessitate the use of an interposed strip.

Referring now to the drawings, Fig. 1 illustrates in side elevation, a preferred form of apparatus for carrying out our improved method; Fig. 2 is an end elevation of the apparatus shown in Fig. 1 on a somewhat larger scale, certain parts being broken away to more clearly illustrate the internal construction; Fig. 3 is an enlarged sectional detail, the plane of the section being indicated by the lines 3—3 on Fig. 1; Fig. 4 is an enlarged sectional detail illustrating the ends of the wire ready to be joined by the use of an interposed strip.

We propose to carry out our invention by placing the ends 10 and 11 of the fabric to be

joined upon a block 12, which extends entirely across the width of the fabric, and which is supported upon a work table 13. Disposed above the fabric and extending lengthwise of the seam, we have shown a beam 14, which supports the seam making mechanism for movement across the fabric. The beam, in turn, is illustrated, as having shoes 15, rigidly attached thereto, and slidably supported in girders 16 that are disposed adjacent the ends of the work table, and in turn are carried by columns 17. The girders may comprise channel members, which are placed back to back, and are attached to the opposing faces of the columns. This leaves an opening through which a threaded spindle 20, journalled at 21 and 22 in the columns may extend. A threaded nut 23 is rigidly fastened to each shoe, and is adapted to extend downwardly into the opening between each pair of girders, and is in threaded engagement with the spindle, as is shown in Fig. 2. The spindle and nut form a screw and nut couple by means of which the beam may be adjusted transversely of the seam. One of such couples is positioned at each end of the beam, and each spindle is provided with a hand wheel 24 by means of which it may be rotated.

The seam forming mechanism comprises a carriage 30, which is shown as a box-like member that extends around the beam and that has wheels 31 journalled therein, and bearing on the lower flanges 32 of the beam 14. The carriage supports an electric motor 33, and a gear reduction unit, indicated in general at 34, and has an opening in the top walls thereof through which a pinion 35 projects. The pinion is operatively connected to the motor through the gear reduction unit, and is adapted to mesh with a rack 36, that is fastened to the top of the beam.

Depending from the carriage is a cradle, which is illustrated as having a top member 40, end members 41 and bottom members 42; the end members being connected to the top and bottom members at 43, and 44 respectively. The vertical position of the cradle with reference to the carriage may be controlled by adjusting screws 45, such adjustment being useful for controlling the pressure at which the work is engaged. The lower cradle members 42 comprise guideways in which heat conducting blocks 46 are carried. Each block has a T-shaped head 47 which engages the corresponding passageway 48 in the bottom members so as to suspend the blocks whenever the cradle is raised sufficiently to clear the work. The blocks 46 have a small opening 49 therebetween through which heat preferably

in the form of a flame from a torch 50 may be played upon the work. The torch, in turn, is shown as being carried by an inverted channel member 51 that straddles the blocks, and is rigidly fastened thereto.

The heat conducting blocks and the associated torch are movable, as a unit, with reference to the cradle, so as to facilitate the application of heat in those seams for which a continuous movement is not suited. However, in other seams, where continuous movement can be applied, provision is made for clamping the blocks to the cradle, whereupon the heat can be applied continuously, and with a uniform rate as the carriage is moved along the beam. Such locking mechanism may comprise a set screw 52, which is carried by one of the bottom members 42, and which is adapted to engage one of the blocks 46.

To make a seam by means of a machine, embodying our invention, the two ends of the fabric are laid upon the block 12, and the rest of the cloth is passed around rolls 53, which are carried by removable shafts supported on the work table. The ends are carefully placed in opposition to each other, and are then held in such position by weights 54, which rest upon the fabric, and which extend across the width thereof, and on each side of the seam. The weights, however, are spaced sufficiently far apart to permit movement of the cradle therebetween during the seam forming operation.

Where the seam is to be made with an interposed strip containing fusible material, such as is shown at 60 in Fig. 4, the strip is positioned between the ends of the fabric at the time the weights are laid on the cloth. Thereupon, the hand wheels 24 are operated, if necessary, to adjust the beam transversely with respect to the seam. The adjusting screws 45 are then operated to lower the cradle until the heat conducting blocks 46 engage the work with a sufficient degree of pressure to conduct the heat therefrom, when the gas is ignited, and yet to permit them to be slid along the cloth progressively during the heating operation.

Whenever, the operator desires to actuate the mechanism intermittently across the fabric, the motor is operated intermittently, and then the torch unit is moved by hand along the cradle to weld or solder a predetermined length. Then, the warp pickets, in advance of the torch, are adjusted progressively, and the cradle is advanced to a new section during which time the torch is not applied to the work. Thereupon, the torch until is moved with respect to the cradle until another section is treated. In other types of seams, however, which are adapted for continuous seaming, the torch unit is rigidly fastened to the cradle by the clamping screw 52, and then the motor is operated to move the cradle continuously across the fabric. During such movement, an operator may make such final adjustment to the position of the warp pickets, as may be necessary to maintain the desired degree of alignment in advance of the torch.

65 We claim:—

1. A method of making a seam in wire fabric, comprising interposing a strip between the ends of the fabric to be joined, abutting the ends of the fabric against opposite sides of the strip and progressively moving a heat applicator with substantially uniform velocity entirely across the fabric to unite the strip to the fabric.

2. A method of making a joint for wire fabric, comprising interposing a strip containing fusible

material between the ends of the fabric to be joined, and positioning a heat applicator adjacent to the interposed strip, and then moving the applicator at a substantially uniform velocity across the entire joint, the applicator being regulated to furnish sufficient heat to fuse the strip to the fabric without making objectionable changes in the molecular structure thereof.

3. An apparatus for making a seam in wire fabric, comprising a trackway disposed above the fabric, a carriage movable along the trackway, an electric motor for operating the carriage, and means mounted suspended from the carriage for applying heat to the fabric adjacent the joint, said means including heat conducting blocks that are movable with the carriage.

4. A device of the character described, comprising in combination a carriage, means for supporting it in spaced relationship to the contacting ends of the fabric that are to be joined, means for moving the carriage longitudinally of the joint, and other means for moving the carriage transversely of the joint.

5. A device for applying heat to a joint in wire fabric, comprising a torch, a carriage for holding the torch above the fabric, means for moving the carriage with uniform velocity along the joint, and other means for selectively moving the carriage transversely of the joint.

6. A device of the character described, comprising in combination, a flat continuous support for the fabric to be joined, means for slidably engaging the surface of the fabric on each side of the joint, a torch associated with said means, and mechanism for moving the torch longitudinally of the joint.

7. A device of the character described, comprising in combination, a flat continuous support for the fabric to be joined, means for slidably engaging the surface of the fabric on each side of the joint, a welding or soldering means associated with said last named means, and means for moving said welding or soldering means longitudinally of the joint.

8. An apparatus for making a seam for wire fabric comprising a beam that is spaced from the fabric, a rack carried by the beam, a carriage movably supported on the beam, an electric motor mounted on the carriage, gearing operatively connecting the motor to the rack, a cradle depending from the carriage, means mounted on the cradle for uniting the ends of the fabric, and means for adjusting the beam transversely of the joint.

9. An apparatus for making seams for wire fabric, comprising in combination, a beam that is disposed above the fabric to be joined, a carriage movable along the beam, a cradle suspended from the carriage, means for adjusting the cradle vertically with reference to the work, other means for adjusting the cradle laterally with reference to the work and a torch movably positioned on the cradle.

10. An apparatus for making seams for woven wire fabric, comprising in combination, a beam, means for supporting it above the fabric to be joined, mechanism for adjusting the beam transversely of the joint, a carriage movably positioned on the beam, mechanism for moving the carriage along the beam, a cradle suspended from the carriage, a guideway on the cradle, and a member movable along the guideway, and having a portion thereof slidably engaging the top of the fabric and a torch carried by said member.

11. A method of making a seam in wire fabric,

comprising bringing together the ends of the fabric to be joined, against the opposite sides of an interposed strand, and progressively moving a heat applicator with substantially uniform velocity entirely across the fabric to unite the ends and the strand together.

12. An apparatus for making a seam in wire fabric comprising a carriage, means for supporting the carriage for movement along the fabric,

heat conducting blocks and a heat applicator movable with the carriage, and an electric motor for operating the carriage with uniform velocity across the fabric, whereby the heat applicator unites the strand to the edges while the carriage is in motion.
